ATTORNEYS,

UNITED STATES PATENT OFFICE.

ROBERT FERNANDEZ, OF BROOKLYN, NEW YORK.

WAGON-GEAR.

SPECIFICATION forming part of Letters Patent No. 395,045, dated December 25, 1888.

Application filed October 16, 1888. Serial No. 288,209. (No model.)

To all whom it may concern:

Be it known that I, ROBERT FERNANDEZ, of Brooklyn, in the county of Kings and State of New York, have invented a new and Improved Wagon-Gear, of which the following is a full, clear, and exact description.

Reference is to be had to the accompanying drawings, forming a part of this specification, in which similar letters of reference indicate corresponding parts in all the figures.

Figure 1 is a side elevation of the front axle, the front portion of the body, and the front running-gear of a wagon constructed in accordance with my invention. Fig. 2 is a sectional elevation of the same, taken on the line $\alpha\alpha$ of Fig. 1. Fig. 3 is a side elevation showing a modification, and Fig. 4 is a transverse sectional elevation of the same.

The invention will first be described in connection with the drawings, and then pointed out in the claims.

The axle A and the fifth-wheels B B' may be of the ordinary or of any approved construction. Upon the head-block C is mounted the elliptical spring D, which supports the body E in the usual manner. In addition to this spring I use a yielding support to relieve the spring D. In Figs. 1 and 2 this yielding support is in the form of a semi-elliptical spring, F, arranged central to the wagon. The lower half of this semi-elliptical spring is secured to the upper fifth-wheel, B', by a clip, G. A block, G', is placed between the spring and said fifth-wheel to serve as a bed-piece or support for the spring. A bent binding-plate, G², is passed over the center of the spring D, and is bolted at its forward end to the block G', and is held at its rear end by the clip G, so that the lower halves of the springs F D are securely united and practically act as one, the spring F serving to strengthen the spring D and relieve it of a part of its load. The end of the upper half of the spring F is secured to the body E and the upper half of the spring D by a through-bolt, d, (shown in dotted lines in Fig. 1,) and the front end of one leaf of the spring is ex-

tended to form the front brace, f, which is bolted to the body E, as shown in Fig. 1.

The body E is braced to the apex of the semi-elliptical spring F by the two opposite diagonal brace-rods H, which brace and support the body E and cause the body E to react upon the said elliptical spring and prevent it from lateral displacement. In Figs. 3 and 4 these rods H are attached at their upper ends to the bolster M and at their lower ends to the opposite ends of a bolt, N, which slides in a slot, N', in the reach N². The body E is supported still further from the semi-elliptical spring F by means of the leg J, Figs. 1 and 2, the lower end of which touches or nearly touches the upper surface of the spring F, and is held from rearward deflection by the stop i, formed upon or secured to the upper leaf of the semi-elliptical spring, as shown clearly in the drawings.

In Figs. 3 and 4, for a yielding support in place of spring F, as in Figs. 1 and 2, I use the crossed plates or rods O and S and the upper and lower reaches, N² P. The plates or rods O are pivoted at their lower ends to the reach N² by the bolt Q, and their upper ends are connected together by the bolt R, passed through the slot R' in the upper reach, P. The upper ends of the plates or rods S are attached to the upper reach, P, by a bolt, T, while their lower ends are attached to above-mentioned bolt N, which holds the rods H and which moves in the slot N'. The plates or rods O and S are secured together in the center by the bolt U, so that when the spring D is more than ordinarily depressed by the load and the bolts R and N reach the rear ends of the slots R' N' the plates or rods O and S fulcrum over the central bolt, U, and furnish a yielding support for the load in addition to the spring D, and thus obviate the usual danger of breaking the latter.

Having thus described my invention, what I claim as new, and desire to secure by Letters Patent, is—

1. The running-gear of a wagon, the usual spring, D, and a yielding support or guard

for the spring, connected with the main reach and also with an upper reach at the bottom of the box, in combination with side diagonal braces, H, for the body of the wagon, substantially as described.

5 2. The semi-elliptical spring F, connected to the fifth-wheel and body of the wagon, in combination with the side braces, H, connecting the spring F with the body, substantially 10 as described.

3. The combination, with the semi-elliptical spring F, of the leg J, attached to the body and resting upon the said spring, substantially as described.

ROBERT FERNANDEZ.
